US00D678898S

(12) **United States Design Patent**
Walsh et al.

(10) **Patent No.:** **US D678,898 S**
(45) **Date of Patent:** **** Mar. 26, 2013**

(54) **CONTEXT-ADAPTIVE USER INTERFACE
FOR A PORTION OF A DISPLAY SCREEN**

(75) Inventors: **Daniel Walsh**, San Francisco, CA (US);
Liang-Cheng Lin, Milpitas, CA (US);
Philip Brian Dils, San Francisco, CA (US)

(73) Assignee: **Adobe Systems Incorporated**, San Jose, CA (US)

(**) Term: **14 Years**

(21) Appl. No.: **29/378,232**

(22) Filed: **Nov. 1, 2010**

(51) LOC (9) Cl. **14-02**

(52) U.S. Cl. **D14/487**; D14/490; D14/491

(58) **Field of Classification Search** D14/485-495;
715/205, 762, 835

See application file for complete search history.

(57) **CLAIM**

The ornamental design for a context-adaptive user interface for a portion of a display screen, as shown and described.

DESCRIPTION

FIG. 1 is a face view of a context-adaptive user interface for a portion of the display screen, showing our new design. Subject matter shown in broken lines, including text shown in broken lines, forms no part of the claimed design.

1 Claim, 1 Drawing Sheet
